UNITED STATES PATENT OFFICE.

FRANK E. KOENEKE, OF MILWAUKEE, WISCONSIN, ASSIGNOR TO SELMA KOENEKE, OF MILWAUKEE, WISCONSIN.

INKING-MACHINE FOR TYPE-WRITER RIBBONS.

No. 900,936.

Specification of Letters Patent.

Patented Oct. 13, 1908.

Application filed March 8, 1906. Serial No. 304,870.

To all whom it may concern:

Be it known that I, FRANK E. KOENEKE, of Milwaukee, Wisconsin, have invented an Inking-Machine for Type-Writer Ribbons, of 5 which the following is a specification.

This invention relates to a mechanism for applying to strips of fabric or ribbon an ink composition for the purpose of manufacturing the ink-ribbons of type-writer machines. 10 It has for its main objects to provide a simple and inexpensive machine which shall perform the functions of thoroughly incorporating the ink into the fibers of the ribbon, applying just enough and no more, and reeling it automatically upon a spool to the proper length for one ribbon; and to perform these functions more perfectly and with less mechanism than heretofore existing machines.

20 I particularly design to make a machine so light, compact, simple and low in cost that it can be profitably purchased by regular business houses using type-writers, and the ribbons manufactured by themselves for their 25 own use.

The principal features of my machine consist in a reel for containing the blank strip of fabric or ribbon which is to be inked, an ink-well containing a roller which is adapted, in 30 contradistinction to any previously existing machine, to apply ink in excess to only a fraction of the total width of the ribbon, and a set of rubbing and distributing rolls which 35 perform the function of distributing said ink over the total width of the ribbon, and thoroughly incorporating it therewith; together with a reeling mechanism adapted to take up the ribbon as fast as it issues from the rolls and wind it upon a spool for use.

40 Other subsidiary features are also involved, which will be best understood from the following specification and claims.

In the accompanying drawings I have illustrated two embodiments of my invention, and herein Figure 1 is a front elevation of the machine, Fig. 2 is a plan view thereof, showing the upper bearing-block lifted off on one side and a part of the other side broken away; Fig. 3 is a longitudinal vertical median section through the same; Fig. 4 is a left end elevation of the same, Fig. 5 is a plan view of the ink-well; Fig. 6 is a vertical transverse median section through the same, the ink-roll being shown in elevation;

Fig. 7 is a fragmentary side elevation of the 55 same with a portion of the front wall removed; Fig. 8 shows a piece of ribbon which has partly passed through the machine, to illustrate the distribution of the ink thereon; Figs. 5, 6 and 7 show also different forms of 60 ink-roll which may be used. Fig. 9 is a longitudinal vertical median section of another construction of the machine with some improvements not shown in the other form; Fig. 10 is a fragmentary transverse section 65 therethrough on the line 10; Fig. 11 is a plan view of the ink-well used with this form of machine; and Fig. 12 is a transverse median section therethrough on the line 10 of Fig. 9.

In these drawings every reference character 70 refers always to the same part.

The apparatus, as shown in Figs. 1 to 8, comprises a pair of side frames consisting of upright plates 11 having bolting-ears 11^a at the bottom and flanges 12 along the upper 75 edge, a pair of lower bearing-blocks 13 secured to the flanges 12 by cap-screws 14; a pair of upper bearing-blocks 15 mounted on the lower bearing-blocks and secured thereto by cap-screws 16; and a pair of bars 17 which 80 also serve to secure the blocks 13 and 15 together by means of cap-screws 18, and which carry set-screws 19, the purpose of which will be designated further on. The flanges 12 and bearing-blocks as here shown are set on 85 an incline, but this is immaterial to my purpose. Upon these frames and, generally speaking, between them are mounted all the operative mechanisms and devices connected therewith. The frames are joined together 90 by three shoulder-bolts 20 passing through holes therein and secured by nuts 21 on each end; and a fourth bolt 22 at the lower left-hand corner which is the equivalent of one of the bolts 20 except that it carries a sleeve 23 95 taking the place of the shoulder, to permit said bolt being withdrawn from the frame separately in order to enable the ink-well to be removed and inserted.

On the frame-plates 11 near the center is 100 mounted an arbor 24, and on this arbor is mounted, and fixed to it nonrotatably, a spool 25, which in operation carries a roll of the ribbon or fabric 26 which is to be inked. The arbor 24 extends beyond the frame-plate 105 at the rear and carries a crank 27 and having a handle 27^a for the purpose of rotating the spool in order to wind ribbon thereon, the

spool being provided with any proper device for connecting the end of the ribbon with the hub thereof, and as such devices are well known to the art, it has not been thought necessary to illustrate one herein.

The bearing-blocks 13 and 15 have cylindrical sockets in which are mounted a pair of rolls 28 and 29 whose axles 30 and 31 are geared together by means of spur-gears 32 and 33, these gears being of the same size, and to one of the axles is applied means for rotating the same; for example, a crank 34 keyed to the axle 30 and having a handle 35. The rolls 28 and 29 are of different diameter, the roll 28 being the larger and provided with a covering 36 of proper material to act in conjunction with the surface of the roll 29 to rub the ink into the pores of the fabric, and I have found vulcanized rubber to be the most suitable for this purpose. It will be observed that the two rolls, owing to the gear connection, rotate at the same angular velocity, and as the roll 28 is larger than the roll 29, it will have a greater peripheral speed, thus bringing about a differential speed, producing a rubbing action between the two rolls. The roll 29 is pressed resiliently against the roll 28 by its mountings, which comprise a pair of bearing-blocks 36 sliding in recesses 38 in the blocks 13 and 15, compressed coiled-springs 39 mounted in tubular recesses in the bearing-blocks, as shown; an abutment-block 40 for each spring, mounted in the same recess; and the set-screws 19, which press against their respective blocks and form means for adjusting the spring-pressure.

The inking means comprises an ink-well 41 which is completely covered and inclosed except for an opening 42 in the center of the top, through which projects an ink-roll 43 mounted on an-axle 44 which is journaled in a pair of saddles 45 on each side of the well, which may be fixed in place by means of solder or otherwise. The width of this roll 43 is only a small fraction of the peripheral width of the ribbon; for example, with a ribbon one and one-half inches in width, the peripheral width of the roll 43 would be one-sixteenth to one-eighth of an inch, depending on the character of the ink, which is designated 46 in Fig. 3. It is sufficient for ordinary purposes to use a simple roll, designated 43' in Fig. 5, which is of fixed and permanent width; this roll being adjusted to the proper width for a given kind of ink and width of ribbon and being changed to one of a different width when these conditions are altered. In Figs. 6 and 7, however, the roll is made of adjustable peripheral width, the axle 44 being provided with a flange 47 and a screw-thread 48 engaged by a nut 49 between which flange and nut are gripped a plurality of thin disks 50, the number of which may be adjusted as desired. Clamping washers 51 may be inserted on each side

of the disks. It will be observed that the upper surface of the ink-well is preferably given a certain convexity and there may be raised flanges 52 at the sides to hold up the sides of the ribbon and keep the inked center 70 from touching the top of the well.

To the front frame 11 are bolted a pair of bracket-arms or bars 53, 54, which carry the winding spool A and a spring motor for operating it. The bars 53 and 54 are secured 75 by means of screws 55 having nuts 56 and sleeves 57 whereby the front bar 53 is held at a distance from the face of the frame-plate. The motor here shown comprises a main arbor 58 journaled in the bars 53 and 54, and having loosely mounted thereon a gear-wheel 59 and a sleeve 60 which carries a pinion 61. The pinion 61 is operatively connected with and driven by the wheel 59 through a lantern pinion 69 and gear 70, both mounted on a countershaft 68 and meshing with the gear 59 and pinion 61 respectively; and the gear 59 is itself driven by a spiral spring 90 secured at its inner end to the arbor 58 and at its outer end to a pin 91 on the side of the gear 59. The arbor 58 also has fixed thereto on the front side of the bar 53 a ratchet-wheel 62 and a crank 63 having a handle 64, and with the teeth of said wheel 62 co-operates a pawl 65 pivoted on a screw 66 and having a pin 67 extending laterally from it, by which the body 65 is grasped when it is desired to release and unwind the spring 90. The delivery-spool A, which receives the finished ribbon, is set on the sleeve 60 by friction merely, so that it can be readily pulled off and replaced by a new one, it being understood that the turning moment on the sleeve is very light and only sufficient to take up the slack of the 105 ribbon as it comes from the machine.

In order that the motor may be checked and held stationary while a spool is being removed and a new one put in place, I provide a pawl 71 pivoted on one of the distance-sleeves 57 and having a tooth 71^a which engages between the teeth of the gear 59 to hold the same against turning. A pin 71^b is attached to the pawl, by which it may be turned into this position or removed therefrom. When it is desired to remove a filled spool and put a new one in place, the pawl 71 is turned into the position shown in the full lines, and the torsion being so taken off from the sleeve 60, the ribbon can be relaxed and cut and the filled spool replaced by an empty one.

In Figs. 9 to 12 is shown a somewhat different form of machine, having frame-plates 11' which combine in one piece the parts 11, 125 13, 15 and 17 of the previous form. The bolts 20 and 22, sleeve 23, arbor 24, spool 25, and rolls 28 and 29 are identical with those already described, the roll 28, however, being mounted directly in a bearing-hole in 130

an enlargement 72 along the upper portion of each frame-plate, and the roll 29 being similarly mounted in a block 37', which slides in a rectangular aperture 38' in the 5 frame-plate, and is provided with a flange-lug 73 along its upper and lower inner edges which engage in similarly formed rabbets 74 at the edges of said aperture. This block is kept pressed toward the roll 28 by means 10 of a spring 39' located in a tubular bore 75, and which abuts on one end upon the block and on the other end upon the end of a set-screw 19' which engages and threads into the end of the bore 75 and is provided with a 15 cylindrical end 76 extending into the un-threaded portion thereof.

In place of passing the ribbon to be inked around the bolts 20 and 22, there is herein provided a form of ink-well 41 which extends 20 between the bolts 20 and 22 and carries a pair of rollers 77, 78 over which the ribbon passes, these rollers being located on opposite sides of the ink-roller 43'', which latter is here simply a thin disk frictionally pressed 25 upon the shaft 44' turning in stirrups 45', and said disk may be readily removed from the shaft. The rollers 77, 78 are each provided with flanges 79 at their ends, the distance between the flanges being the exact 30 width of the ribbon, whereby the ribbon is maintained truly central in passing over the ink-roller 43''. The rollers 77 and 78 are carried on shafts 80 which are mounted in channel-shaped strips 81, 82 secured to the 35 upper side of the inkwell. The strip 82 on the delivery side of the ink roller is differently formed from the strip 81 in that it has a lateral extension 83 turned upright to form a wiping-edge, which is of just the proper 40 height to touch the underside of the ribbon as it passes and scrape off any excess of ink therefrom, the ink so removed falling back into the well through the central opening 42'. Moreover, I provide the edges of this 45 opening with downturned flanges 84 which dip below the normal level of ink in the well and prevent the same from being spilled by any sudden movement, as well as from evaporating unnecessarily. At the end of the 50 well are provided clips 85 which engage under the bolts 20 and 22 to hold the well against the upward tension upon the ribbon. In this form of machine I also provide the upper pair of bolts 20 with roller-sleeves 86 55 having flanges 87 set distanced at the width of the ribbon, which serve to better carry it over the bolts and to maintain it central. In this form also the delivery-spool A, is made to turn in a right-handed direction, this 60 being, however, immaterial.

The operation of the apparatus has been sufficiently hereinabove explained, and will be further elucidated by a consideration of Fig. 8, which shows a portion of the ribbon 65 26 having a central streak of ink 88 depos-

ited thereon by the roll 43, and subsequently spread and distributed at 89 by the action of the rolls 28 and 29. The action of the machine can be so exactly regulated as to cause the ink only to spread over a portion of the 70 width of the ribbon, leaving, for example, blank edges 90 along the selvage portion, which it is not desired to use for inking the type. In this manner I may also make multiple color ribbons by distributing different 75 colored streaks of ink either simultaneously or successively along the different points in the width of the ribbon, and subsequently spreading them by the same set of rolls 28 and 29, and two or more narrow ink-wells 80 containing the different colors of ink can be placed side by side for this purpose.

I do not wish it understood that my invention is limited to the use of all the above described features and constructions for some 85 may be omitted and others may be varied or modified in various ways, as will readily occur to those skilled in the art. I recognize the fact, for example, that the streak of ink 88 distributed upon the ribbon need not 90 be continuous, but may form a series of separate dabs, as would be done by a notched roller.

Having thus described my invention, what I claim as new and desire to secure by Letters Patent, is:

1. The process of inking typewriter-ribbons which consists in providing a narrow strip of the width of the ribbon with an excess of ink and thereafter passing the strip 100 between a pair of rolls turning at different peripheral speeds, whereby such ink is distributed evenly over the width of the ribbon.

2. In a ribbon-inking machine, the combination of an ink-roller narrower than the 105 ribbon, means for delivering ink to the periphery thereof, means for passing the ribbon over said roller, and a pair of distributing rollers through which the ribbon is subsequently made to pass and by which the ink 110 is distributed over the width of the ribbon.

3. In a ribbon-inking machine, the combination of an ink-roller narrower than the ribbon, means for delivering ink to the periphery thereof, means for passing the ribbon 115 over said roller, and a pair of distributing-rollers through which the ribbon is subsequently made to pass and by which the ink is distributed over the width of the ribbon, said rollers being caused to move at different peripheral speeds.

4. In an inking-machine, the combination of a pair of rolls one of which has a yielding surface, means for resiliently pressing said rolls together, and means for turning said 125 rolls at different peripheral speeds.

5. In a ribbon-inking machine, the combination of a pair of rolls, sliding-pieces in which one of said rolls is journaled, compression - springs acting upon said sliding- 130

pieces to press the roll mounted therein against the other roll, and means for turning said rolls at different peripheral speeds.

6. In a ribbon-inking machine, the combination of an ink-roll having an active edge narrower than the width of the ribbon to be inked, means for delivering ink to the periphery of said roll, means for passing a ribbon over said roll whereby a portion thereof becomes coated with an excess of ink, and a pair of distributing rolls through which the ribbon subsequently passes and by which the ink is distributed over the width of the ribbon, in combination with means for silently taking up and winding the ribbon delivered from said rolls.

7. In a ribbon-inking machine, the combination of an inkwell, an ink-roller rotating partly immersed therein and having a width narrower than the ribbon to be inked, means for passing the ribbon over said roller, and a pair of distributing rolls through which the ribbon subsequently passes, one of said rolls having a yielding surface and turning at a different peripheral speed from the other roll.

8. In a ribbon-inking machine, the combination of an inkwell, an ink-roller rotating partly immersed therein and having a width narrower than the ribbon to be inked, means for passing the ribbon over said roller, a pair of distributing rolls through which the ribbon subsequently passes, and means for winding the ribbon as it comes from said rolls at a substantially constant tension.

9. In a ribbon-inking machine, the combination of a pair of side-frames, bolts securing them together in parallel relation, a spool rotatably mounted between said frames, means for turning said spool to wind ribbon thereon, an ink-well located below said spool, a roller turning in said ink-well, means for passing the ribbon over said roller, distributing-rolls mounted between said frames above said spool, means for turning said distributing rolls, and means for rotating a delivery-spool upon which the finished ribbon is reeled.

10. In a ribbon-inking machine, the combination of a pair of side-frames, means for securing said frames in parallel relation, a pair of rolls between said frames and one of which has a yielding surface, a pair of journal-blocks in which one of said rolls is mounted, said blocks sliding in said frames, a pair of springs operating to press the respective blocks toward the other roll, and a pair of set-screws operating upon the respective springs to adjust the tension thereof.

60 11. In a ribbon-inking machine, the combination with inking-mechanism of an arbor, a sleeve mounted on said arbor and carrying a gear, a second gear mounted independently on said arbor, a spring operating to rotate said second gear, and gearing connecting said

second gear with the first whereby said sleeve is rotated; said sleeve being arranged to receive and frictionally hold the nave of a delivery-spool.

12. In a ribbon-inking machine, the combination with inking-mechanism of an arbor, a sleeve mounted on said arbor and carrying a gear, a second gear mounted independently on said arbor, a spring operating to rotate said second gear, and gearing connecting said second gear with the first whereby said sleeve is rotated; said sleeve being arranged to receive and frictionally hold the nave of a delivery-spool, and a pawl adapted to engage the teeth of one of the gears whereby the tension is removed from said sleeve.

75 13. In a ribbon-inking machine, an inking-device comprising a vessel adapted to contain ink, said vessel having an opening in the center and depending flanges at either side of said opening, said flanges dipping below the normal level of the ink in said vessel, and an ink-roller mounted to rotate in said opening.

85 14. In a ribbon-inking machine, an inking-device comprising a vessel adapted to contain ink, said vessel having an opening in the center and depending flanges at either side of said opening, said flanges dipping below the normal level of the ink in said vessel, an ink-roller mounted to rotate in said opening, and a pair of guide rollers mounted on opposite sides of said ink-roller.

95 15. In a ribbon-inking machine, an inking-device comprising a vessel adapted to contain ink, said vessel having an opening in the center and depending flanges at either side of said opening, said flanges dipping below the normal level of the ink in said vessel, an ink-roller mounted to rotate in said opening, a pair of guide-rollers mounted on opposite sides of said ink-roller, and a wiping-edge projecting into proximity to the ribbon on the delivery side of said opening whereby excess of ink is removed from the ribbon and caused to return to the well.

100 16. In a ribbon-inking machine, an inking-device comprising a vessel adapted to contain ink, said vessel having a central opening and flanges on either side of said opening depending below the normal level of ink in said vessel, a shaft mounted to rotate in said vessel between said flanges, a narrow inking-disk mounted on said shaft and dipping in the ink in said vessel, a pair of flanged guide-rollers located on opposite sides of said opening and having a length distanced much greater than the width of said disk, and an upright wiping-edge on one side of said opening projecting into proximity to a ribbon which passes over said ink-roller and under a guide-roller.

115 17. A ribbon-inking machine comprising, in combination, a pair of frame plates, a plurality of distance - bolts securing them in parallel relation, an arbor mounted between 120

said plates in the approximate center thereof, means for rotating said arbor, a reeling-spool carried on said arbor, an ink-well below said arbor and carrying a narrow ink-roller, a pair of distributing rolls journaled between said plates above said reeling-spool, means for rotating said distributing-rolls, a spring-motor mounted on one of said frame-plates and having an arbor adapted to receive a delivery - spool, and one or more flanged guide-rollers mounted on said dis-

tance-bolts; the ribbon being caused to pass from said reeling-spool successively over said ink-roller, between said distributing-rolls and upon said delivery-spool and being 15 guided in its passage by said flange rollers.

In witness whereof I have hereunto set my hand this fifth day of March, 1906.

FRANK E. KOENEKE.
